ALBERT STUBBS, OF WINSFORD, ENGLAND, ASSIGNOR TO WESTINGHOUSE ELECTRIC & MANUFACTURING COMPANY, A CORPORATION OF PENNSYLVANIA.

FEED-WATER SYSTEM.

Application filed December 17, 1924, Serial No. 756,480, and in Great Britain February 1, 1924.

This invention relates to feed water systems for condensing steam plant, particularly to that type of system wherein differences between the supply of feed water by the condenser extraction pump and the demands made upon such supply by the boiler feed pump are compensated by variations of water level in a stand pipe and surge tank connected with the system between the delivery of the condenser extraction pump and the suction of the boiler feed pump.

In accordance with the present invention sub-atmospheric pressure is maintained in the surge tank and a second surge tank may be provided and connected with the first tank either directly or through the circulatory system, the arrangement when a second tank is provided being such that normal fluctuations are compensated by variations in water level in the first surge tank, whereas abnormal fluctuations are compensated by variations of water level in both tanks. The first tank may conveniently be maintained at sub-atmospheric pressure by connecting it to the vacuum space of the condenser, whereas the pressure in the second tank may conveniently be at or about atmospheric. The first tank is sealed to enable a sub-atmospheric pressure to be maintained therein and the second tank may be partially sealed against atmospheric contamination in any suitable manner, as for instance by means of a float. The connection between the first tank and the feed water system may be made either before or after any feed water heaters which may be incorporated in the system so that the temperature of the water in such tank may be equal to or greater than that corresponding with the absolute pressure in the condenser.

Several forms of the invention are illustrated by way of example in the accompanying drawings each figure of which is a diagrammatic representation of sufficient of the feed water system of a condensing steam plant to enable the application of the invention thereto to be understood.

In each system illustrated 1 is the condenser, 2 the extraction pump, 3 and 4 the suction and delivery pipes respectively of the pump 2, 5 the surge tank, 6 the stand pipe

connecting the surge tank 5 with the delivery pipe 4, and 7 the boiler feed pump, all substantially in accordance with known practice.

In accordance with the invention the upper portion of the surge tank 5 is connected with the vacuum space of the condenser 1 by means of a pipe 8, a second surge tank 9 is connected with the delivery pipe 4 by means either of a single stand pipe 10, as in Figs. 1 and 4, or of two stand pipes 10 and 11, as in Figs. 2 and 3, and a non-return valve 12 is inserted in the delivery pipe 4 between the pump 2 and the stand pipe 6.

In the system illustrated by Fig. 1 the surge tank 5 is connected with the surge tank 9 by an overflow pipe 13 and a non-return valve 14 is inserted in the stand pipe 10. To insure that the difference of pressure which exists in the tanks does not cause water to flow from the tank 9 into the tank 5 the highest point of the pipe 13 is raised at least 34 feet above the normal water level in the tank 9 and to obviate the possibility of water flowing from the tank 5 to the condenser 1 the pipe 8 is connected with the tank 5 at a higher level than the connection between the pipe 13 and the tank 5 and the highest point of the pipe 8 is located above the highest point of the pipe 13.

With this arrangement, under normal conditions of operation, the water level in the tank 5 fluctuates about a mean position in compensation of normal fluctuations of supply and demand in the circulatory system.

Under such conditions, the discharge pressure of the extraction pump 2, which corresponds to the inlet pressure of the boiler feed pump 7, is greater than the static pressure of the water contained in the second surge tank 9 and hence the check valve 14 is retained in a closed position and there is no flow of water from the surge tank 9 to the boiler feed pump. During this time all fluctuations are taken care of by the surge tank 5 and, as this tank is vented to the condenser 1, all of the vapor liberated from the condensate in the surge tank is returned to the condenser and is thus retained in the system. Furthermore, by venting the surge tank 5 to the condenser rather than to the atmosphere, en-

trainment of air in the water of the system is avoided and as a consequence the corrosive action of the feed water upon the condensers, the tanks, the pumps, the boilers, etc., is materially reduced.

Should the amount of condensate discharged by the extraction pump 2 be materially in excess of that demanded by the boiler feed pump 7, the excess water is conveyed 10 to the surge tank 5 and, upon the same becoming substantially filled, the excess overflows through the pipe 13 into the second surge tank 9, whereby it is retained in the system. As power plants have heretofore been arranged, this excess would be lost from the system but by my novel arrangement of employing two surge tanks, this excess is conserved. As the surge tank 5 is arranged a distance 20 above the second surge tank somewhat in excess of thirty-four feet, there is no danger of the water in the second surge tank 9 being drawn into the surge tank 5 by the sub-atmospheric pressure prevailing therein. Furthermore, as the overflow pipe 13 enters the surge tank 5 a distance somewhat below the vent connection 8, the excess water will escape 25 through the overflow and not through the vent pipe.

When the amount of water discharged by 30 the extraction pump 2 is considerably less than the amount required by the boiler feed pump 7, then the surge tank 5 temporarily compensates for this deficiency until such time as the pressure in the pipe 4 becomes 35 less than the static pressure of the water in the second surge tank 9 whereupon the check valve 14 is opened to permit the water in the second surge tank 9 to compensate for the deficiency.

40 It is apparent from the foregoing description that a feed water system so arranged possesses considerable merit over those systems heretofore employed because, the surge tank 5, which takes care of all normal fluctuations 45 in the demands of the system, is not vented to the atmosphere nor is its overflow connection connected to some point outside the system. On the other hand, this tank is so arranged that all vapor and all overflow condensate are retained while the entraining of 50 air in the condensate is avoided. In addition, the system is so flexible that even though an abnormal fluctuation should take place, the second surge tank immediately acts 55 to compensate for such abnormal changes. In this way, the boiler feed pump is always supplied with the required amount of feed water and the system operates with an extremely high thermo dynamic efficiency.

60 In the system illustrated by Fig. 2 the tanks 5 and 9 are located at substantially the same level and the pipe 8 is in the form of an inverted U-bend the highest point of which is approximately 34 feet above the maximum 65 water level in the tank 9. A non-return valve

14, similar to that employed in the system illustrated by Fig. 1 but adapted to operate in the opposite direction, is inserted in the pipe 10 and a valve 15 controlled by a float, 15', in the tank 5 is inserted in the pipe 11.

70 With this arrangement normal fluctuations in supply and demand are compensated as before while considerable excess of supply over demand will cause the water completely to fill the tank 5 and to rise to such an extent 75 in the pipe 8 as to create a pressure in the pipe 4 sufficient to open the valve 14 and admit any further excess into the tank 9. In the event of the demand by the feed pump 7 exceeding the supply available from the extraction pump 2 the supply will first be augmented from the tank 5 until the latter is completely or nearly empty when the float controlled valve 15 will open and the supply will then be augmented from the tank 9.

80 The general arrangement and operation of the system illustrated by Fig. 3 is similar to that illustrated by Fig. 2 except that the pipe 8 is of any convenient formation and a valve 16 which is either controlled by the float 16' 85 in the tank 5 and adapted to be closed when the latter is full, or this valve may be of the type adapted to pass gases whilst closing against liquids is inserted therein.

90 In the system illustrated by Fig. 4 the tank 9 is located at a somewhat higher level than the tank 5 and is connected with the latter by a pipe 13. A valve 16 similar to that described with reference to Fig. 3 is inserted 100 in the pipe 8, a non-return valve 17 is inserted in the pipe 13 preventing the passage of liquid from the tank 9 to the tank 5, and a non-return valve 14 similar to that employed in the system illustrated by Fig. 1 is inserted in the pipe 10.

105 With this arrangement normal fluctuations in supply and demand are compensated as before while considerable excess of supply over demand will cause the water first to fill the tank 5 and close the valve 16 and then to open the valve 17 and flow into the tank 9. In the event of demand by the feed pump 7 exceeding the supply from the extraction pump 2 the supply will first be augmented from the tank 5 until the latter is completely or nearly empty when the non-return valve 14 will open and the supply will then be augmented from the tank 9.

115 In a modification of any of the arrangements herein described two stand pipes may be provided in connection with the tank 5 so that the whole of the condensate may be passed through the latter. This arrangement is of advantage when a feed water heater is placed between the tank 5 and the extraction pump 4 and it is desired to divide the water upon entry into the tank to facilitate further deaeration in those cases where aeration of the main condensate has taken place after leaving the condenser, for exam- 120

ple owing to air leakage at the glands of the extraction pump.

While I have shown my invention in several forms, it will be obvious to those skilled in the art that it is not so limited, but is susceptible of various other changes and modifications, without departing from the spirit thereof, and I desire, therefore, that only such limitations shall be placed thereupon as are imposed by the prior art or as are specifically set forth in the appended claims.

What I claim is:

1. In a feed water system, the combination of a condenser, a pump for receiving condensate from the condenser, a second pump arranged to receive the condensate discharged from the first pump and to discharge said condensate to the system, and two surge tanks communicating with the inlet of the second pump, one of said surge tanks being arranged to compensate for normal fluctuations in the demands of the system and the other surge tank being arranged to compensate for abnormal fluctuations in the demands of the system.

2. In a power system, the combination of a condenser, a pump for removing condensate from the condenser, a second pump for receiving the condensate discharged from the first pump and for discharging said condensate to the system, two surge tanks communicating with the inlet of the second pump, the first of said surge tanks having a sub-atmospheric pressure prevailing therein and being arranged to compensate for normal fluctuations in the demands of the system and the second surge tank having atmospheric pressure prevailing therein and arranged to compensate for abnormal fluctuations in the demands of the system.

3. In a power system, the combination of a condenser, a pump for removing condensate from the condenser, a second pump for receiving the condensate discharged from the first pump and for discharging said condensate to the system, and two surge tanks communicating with the inlet of the second pump, the first of said surge tanks being vented to the condenser and arranged to compensate for normal fluctuations in the demands of the system and the second surge tank being arranged to receive condensate overflowing from the first tank and to compensate for abnormal fluctuations in the demands of the system.

4. In a feed water system, the combination of a condenser, a pump for removing condensate from the condenser, a second pump for receiving the condensate discharged from the first pump and for discharging said condensate to the system, a surge tank freely communicating with the inlet of the second pump, a second surge tank communicating with the inlet of the second pump, and means provided between the second surge tank and

the inlet of the second pump to permit the condensate to flow only in a direction from the second surge tank to the inlet of the second pump.

5. The combination with a feed water system comprising fluid-translating devices arranged in series and a surge tank connected to said system between said fluid-translating devices, of means for maintaining a sub-atmospheric pressure in said tank, a second tank, means for passing a liquid only from the first to said second tank, and means for supplying liquid to said system from said second tank when the supply of liquid in said first tank is inadequate for this purpose. 70

6. The combination with a feed water system comprising fluid-translating devices arranged in series and a surge tank connected to said system between said fluid-translating devices, of means for maintaining a sub-atmospheric pressure in said tank, a second tank, means for passing a liquid only from the first to said second tank, and pressure-responsive means for supplying liquid to said system from said second tank when the supply of liquid in said first tank is inadequate for this purpose. 85

7. The combination with a feed water system comprising fluid-translating devices arranged in series, a surge tank connected to said system between said fluid translating devices, and means for maintaining a sub-atmospheric pressure in said tank, of a second tank connected to said system between said fluid-translating devices, means for supplying liquid to said system from said second tank when the supply of liquid in the first tank is inadequate, and means for passing liquid to said second tank when the delivery of the first fluid translating device exceeds the requirements of the next fluid-translating device and the capacity of said first surge tank. 95

8. A feed water system comprising fluid-translating devices arranged in series, a plurality of tanks connected to said system between said fluid-translating devices, means for producing deaeration in one of said tanks, and means for passing liquid to another of said tanks when the supply of liquid exceeds the capacity of said one of said tanks. 100

9. A feed water system comprising fluid-translating devices arranged in series, a plurality of tanks connected to said system between said fluid-translating devices, means for producing deaeration in one of said tanks, and means for passing liquid from another of said tanks to said system when the requirements of the system exceed the capacity of said one of said tanks. 110

10. A feed water system comprising fluid-translating devices arranged in series, a plurality of tanks connected to said system between said fluid-translating devices, means for producing deaeration in one of said tanks, and means for passing liquid to or from an- 125

other of said tanks accordingly as the supply of liquid or the requirements for liquid exceed the capacity of said one of said tanks.

11. The combination with a condenser and
5 a feed water system for utilizing condensate
as feed water, wherein the system has fluid-
translating devices arranged in series, of a
plurality of tanks connected to said system
between said fluid-translating devices, one of
10 said tanks being closed, a connection from
said one of said tanks to the condenser for
exposing the surface of liquid in said one tank
to condenser pressure, means for maintaining
liquid in another of said tanks at substantially
15 atmospheric pressure, and means for passing
liquid to or from said another of said
tanks accordingly as the supply of liquid or
as the requirements for liquid exceed the ca-
pacity of said one of said tanks.
- 20 12. A feed water system comprising fluid-
translating devices arranged in series, a plu-
rality of tanks connected to said system be-
tween said fluid-translating devices, means
for producing deaeration in one of said tanks,
25 and pressure-responsive means for passing
liquid to another of said tanks when the sup-
ply of liquid exceeds the capacity of said one
of said tanks.

13. A feed-water heating system comprising
30 fluid translating devices arranged in se-
ries, a non-return valve interposed in said
system on the discharge side of the first fluid
translating device, a surge tank connected to
said system between the non-return valve and
35 the second fluid translating device, means for
maintaining a sub-atmospheric pressure in
said surge tank, a second tank, means for pass-
ing a liquid only from the first to the sec-
ond tank, and pressure responsive means for
40 supplying liquid to said system from said
second tank when the supply of liquid in said
first tank is inadequate for this purpose.

In testimony whereof, I have hereunto sub-
scribed my name this 13th day of Nov., 1924.
